UNITED STATES PATENT OFFICE.

GOTTFRIED HENGGI, OF BELLINGHAM, WASHINGTON.

WIRE-REEL.

1,354,555.

Specification of Letters Patent.

Patented Oct. 5, 1920.

Application filed March 15, 1919, Serial No. 282,851. Renewed March 15, 1920. Serial No. 366,042.

To all whom it may concern:

Be it known that I, GOTTFRIED HENGGI, a citizen of the United States, residing at Bellingham, in the county of Whatcom and 5 State of Washington, have invented certain new and useful Improvements in Wire-Reels, of which the following is a specification, reference being had to the accompanying drawings.

10 This invention relates to reels, and particularly to reels for supporting wire such as is used for fencing.

The general object of my invention is to provide a wire reel composed of sections so 15 constructed that the sections may be readily assembled or disassembled to permit the placing of a mass of wrapped wire upon the reel.

And a further object is to provide an improved form of holder for the wire whereby 20 it may be readily carried while the reel is rotating to allow the unwrapping of the wire therefrom.

Other objects will appear in the course of 25 the following description.

My invention is illustrated in the accompanying drawings, wherein:—

Figure 1 is an end elevation of a reel constructed in accordance with my invention 30 and partly broken away;

Fig. 2 is a section thereof on the line 2—2 of Fig. 1;

Fig. 3 is a front elevation;

Fig. 4 is a perspective view of one of the 35 disks 14; and

Fig. 5 is a perspective view of the shaft or bolt 12 and the opposite disk 14.

Referring to these drawings, 10 and 11 40 designate cross pieces of wood or other suitable material which are attached rigidly to each other in any suitable manner, the cross pieces at one end being connected to the cross pieces at the other end by means of longitudinal members 13, triangular in cross 45 section, and being disposed at the intersection of each pair of cross pieces. This is the usual form of the ordinary reel upon which wire is commonly wrapped or wound. As before stated, the object of this invention is 50 to provide means for engaging this reel and supporting it so that the reel may be freely rotated to wind up or unwind the wire thereon. To this end, I provide the oppositely disposed plates 14 and the bolt 12 55 which pass through a central aperture in the cross pieces 10 and 11. Adapted to be ap-

plied over and embrace the cross pieces 11 are the plates 14 which are circular in form and have a raised channel 15 extending diametrically across each plate, the ends of 60 this channel being cut away, that is the channel does not extend across the entire diameter of the plate, but terminates at both ends short of the periphery of the plate. This plate is cut away opposite the ends of 65 the channel, as at 16. The channel 15 of each plate is formed to engage with the square end 17 of the bolt 12. The channel 15 is provided with a transverse opening or 70 passage 18 for the reception of a key 19 whereby each plate 14 is locked to the bolt 12 to rotate therewith, and a crank 20 is riveted, bolted, or otherwise attached to one or both of the disks 14 and specifically to the channel of each disk, as illustrated in 75 Fig. 3.

Each disk is surrounded by an annulus 21, which is held in place by arcuate strips 21^a riveted, bolted, or otherwise disposed on opposite faces of the disk 14. Thus it will be 80 be seen that the annulus 21 is rotatably mounted upon the periphery of the disk 14. These annuli 21 are provided with ears 22, and attached to these ears, as by bolts, are the cross bars 23 and 23^a. The bolts 24 85 which connect the cross bars 23 and 23^a to the ears 22 permit the cross bars to be readily detached at one or both ends from the annuli 21 and thus permit the disks 14 to be disconnected from each other for removal 90 from an empty reel, or for attachment to a new or full reel. It will be noticed that the bar 23^a is longitudinally slotted, as at 25, to form a guide for the wire, and the cross bar 23 forms a handle whereby the reel may be 95 readily carried or supported while the wire is being unreeled therefrom, and the disks 14 and the reel proper rotate freely with relation to these cross bars 23 and 23^a. If it is desired to tighten up on the wire or reel 100 it back to the reel, the cross bars 23 and 23^a may be held firmly while the disks are rotated by means of the crank handles 20 which, as illustrated, have their outwardly extending portions disposed in line with the 105 axis of the reel so as to form bearings for the reel.

A construction of the character described may be readily applied to ordinary forms of wire reel and thus this reel may be 110 conveniently carried and the wire readily unwound from the reel or wound up thereon.

I claim:—

1. A reel of the character described including an axial member, disks supported upon the ends of the axial member and rotating therewith, one of said disks being detachable from the axial member, each of said disks being formed with a diagonally extending channel adapted to receive the cross bar of a wire supporting frame, means 10 for supporting said disks but permitting the disks to rotate, and crank handles attached to the disks.
2. A device of the character described including an axial member, oppositely disposed disks each formed with a diametrically extending channel into which the axial member extends and each disk being formed with four openings disposed in spaced relation to each other on opposite sides of the channel, means for locking the disks to the axial member, and crank handles attached to the disks.
3. A reel of the character described including an axial member adapted to be inserted through the cross bars of a wire supporting frame, disks detachably mounted upon the ends of the axial member and formed to engage said frame and rotate therewith, arcuate plates attached at intervals to the margins of the disks and extending out therefrom on opposite sides thereof to form an interrupted channel, an annulus for each disk disposed in said interrupted channel and slidably engaging the same, 35 and cross bars detachably engaging said annuli.
4. A device of the character described including an axial element, oppositely dis-

posed disks, each formed with a diametrically extending channel into which the axial member extends, means for locking the disks to the axial member, crank handles attached to the disks, an annulus operatively connected to each disk and surrounding the periphery thereof and rotatably engaged with 45 the disk, and cross bars connecting said annuli, one of said cross bars being longitudinally slotted.

5. The combination with a wire reel comprising oppositely disposed crossed bars and longitudinally extending members, of a bolt passing through both sets of crossed bars, disks, each formed with a diametric channel engaging one of said crossed bars and through which the bolt passes, an annulus 55 rotatably engaging the periphery of each disk, crossed bars connecting said annuli and detachably engaged therewith, and crank handles attached to said disks.

6. A device of the character described including an axial member, oppositely disposed disks, each formed with a diametrically extending channel into which the axial member extends, means for locking the disks to the axial member including bolts extending 65 through said axial member, crank handles attached to the disks, an annulus rotatably mounted upon the periphery of each disk, and cross bars connecting said annuli.

In testimony whereof I hereunto affix my signature in the presence of two witnesses.

GOTTFRIED HENGGI.
